DESIGN FOR A VALVE BODY

George Ernst, Livingston Township,
Essex County, N. J.

Application August 18, 1939, Serial No. 86,766

Term of patent 14 years

To all whom it may concern:

Be it known that I, George Ernst, a citizen of the United States, residing in the township of Livingston, in the county of Essex and State of New Jersey, have invented a new, original, and ornamental Design for a Valve Body, of which the following is a specification, reference being had to the accompanying drawing, forming part thereof.

In the drawing,
Figure 1 is a perspective view of a valve body,
showing my new design, and

Figure 2 is an end elevational view thereof.

I claim:

The ornamental design for a valve body, as shown.

GEORGE ERNST.
